FLASH TUBE

Peter I. Hollman, Rockford, Ill., assignor to Geo. D. Roper Corporation, Rockford, Ill., a corporation of Illinois

Original application January 23, 1946, Serial No. 642,941. Divided and this application May 4, 1949, Serial No. 91,373

9 Claims. (Cl. 158—115)

1

This invention relates to lighting devices and more particularly to flash tubes for flashing a flame from one pilot burner to another.

Gas range manufacturers have for some time been attempting to design a satisfactory lighting system for gas ranges and stoves wherein all the burners, that is, the oven burner and broiler burners as well as the top burners, may be lighted from a single constantly burning pilot burner. One of the difficulties encountered in attempting to design such a system has been in the construction of means for flashing the flame from the constantly burning pilot burner to a pilot burner used in lighting one of the main burners. In conventional ranges the constantly burning pilot burner is mounted at the top of the stove and the oven burner and broiler burners are generally located at a lower level in the range. While very little trouble is experienced in flashing flame between laterally spaced burners, considerable difficulty has heretofore been experienced in satisfactorily flashing a flame in a vertical direction. The problem of constructing flash tube means which will operate satisfactorily between the different levels at which the burners are located is complicated by the fact that throughout the country there are a number of different standard gaseous fuels having widely varying combustion characteristics. For example, one part of the country uses natural gas requiring 12 cubic feet of air per cubic foot of gas for combustion and another part of the country uses manufactured gas which requires only 4 cubic feet of air per cubic foot of gas. Thus, the air requirements for different fuels may vary as much as 300%. Furthermore the air requirements for any given fuel may vary from time to time as the pressure conditions of the system or the composition of the gas changes. Because of the many variations encountered flash tubes have not been satisfactory for all prior types of manufactured and natural gases under all service conditions.

An object of this invention is the provision of a flash tube which may be used with a relatively large variety of manufactured and natural gases.

Another object of the invention is to provide a flash tube construction that is simple to construct, that is easy to install, that is rigid and sturdy, and that is relatively inexpensive to manufacture.

Another object of the invention is the provision of a flash tube construction which not only may be used to flash flame between laterally spaced burners, but which positively effects the flash-

2

ing of flame in a vertical direction or component thereof between burners at different levels.

Other objects and advantages of the invention will become apparent from the following detailed description taken in connection with the accompanying drawings, in which—

Figure 1 is a perspective view of an oven lighting system utilizing a flash tube embodying the present invention;

Fig. 2 is an enlarged perspective view of the flash tube showing details of construction;

Fig. 3 is a fragmentary elevation view of one side of the flash tube showing the details of construction;

Fig. 4 is an elevation view of another side of the flash tube;

Figs. 5 and 6 are sectional views taken substantially along the lines 5—5 and 6—6 of Fig. 3, respectively;

Fig. 7 is a perspective view of a modification of the flash tube construction shown in Fig. 2;

Fig. 8 is an elevation view of one side of the flash tube shown in Fig. 8, and

Figs. 9 and 10 are a sectional view taken substantially along the lines 9—9 and 10—10 respectively of Fig. 8.

Referring now to the drawings the invention is shown embodied in a lighting system for a main burner. For purposes of illustrating the invention the main burner is in the form of an oven burner 11 located beneath a conventional oven on a range, not shown, for purposes of simplifying the drawings. The main burner 11 is connected to a gas manifold 12 through a mixing tube 13, a conduit 14, a safety valve 16, a conduit 17, a temperature control and shut-off valve 18 mounted on and in communication with the gas manifold 12. An oven pilot burner 19 at one end of a support arm 21 is disposed adjacent the oven burner 11 for purposes of lighting the latter. The pilot burner 19 is connected to the gas manifold 12 through a passageway 22 in the arm 21, a mixing tube 20 and a conduit 23 connected to the temperature control unit 18. Flash means including a sub-burner 26 is disposed between a constantly burning pilot burner 27, mounted at the top of the range, and the oven pilot burner 19 for igniting the oven burner 11 from the constantly burning pilot burner 27. The sub-burner 26 is connected to the gas manifold 12 through a mixing tube 25, a conduit 28 and an auxiliary valve 29 mounted on the safety valve 16 and which is arranged to be in an open position when the safety valve 16 is closed and in a closed position when the safety valve 16 is open.

55

The temperature control unit 18 may be of any suitable construction. For purposes of illustration it may be of the type shown in the Patent 2,303,011, issued November 24, 1942, to which reference may be had for a detailed account of its construction and mode of operation. In general it comprises a temperature control unit operable to regulate the flow of gas to the main burner 11 in response to temperature changes on a bulb 31 disposed in a conventional manner in an oven (not shown) and connected to the temperature control unit 18 by a capillary tube 32 so that a preselected temperature may be maintained in the oven. The temperature control unit 18 also includes a shut-off valve which controls the flow of gas to the oven burner 11. The shut-off valve is under the control of a control knob 33 extending through a manifold cover plate 34 to be accessible at the front of the range. Normally the knob 33 is biased to an outward position and must be depressed slightly before it may be rotated to open the shut-off valve and preset the temperature control mechanism.

The safety valve 16 may be of any suitable type. For purposes of illustration it is of the electromagnetic type as shown in my copending application, Serial No. 642,941, filed January 23, 1946, to which reference may be had for construction details and its mode of operation. Suffice it to say, herein, that the safety valve 16 is normally biased to a closed position and is opened by a timer mechanism 36 actuated by actuation of the control knob 33. Associated with the safety valve 16 is a thermocouple 37 mounted adjacent the oven pilot burner 19 and connected to the safety valve 16 by suitable leads in a conduit 38. The safety valve is arranged so that when the thermocouple 37 is heated by the oven pilot burner 19 a current is generated in the thermocouple that is sufficient to energize the electromagnet in the safety valve 16 and hold the safety valve in its open position.

The flash means includes a horizontal tube 41 having one end supported on the side of a housing 42 for the pilot burner 21. At its opposite end the tube 41 is connected with an upper end of a generally vertically disposed tubular section 43. The lower end of the tubular section 43 is supported by an inverted funnel-shaped portion 44 forming a part of the sub-burner assembly 26 and overlying the ports 50 of the sub-burner assembly. The sub-burner assembly 26 is in communication with the oven pilot burner 19 through a passageway 46 formed in the arm 21.

In this instance the vertical tubular section 43 is formed by a pair of U or channel-shaped members 51 and 52 telescoped together to form a passageway 53 having an air passageway 54 extending lengthwise of the members 51 and 52, and effecting communication between atmosphere and the central passageway 53. As shown the member 51 includes a bridging portion 55 and spaced side portions 56 in parallel relation and at substantially right angles to the bridging portion 55. The member 52 is formed by a bridging portion 57 and spaced side portions 58 and 59 in parallelism and at substantially right angles to the bridging portion 57. The side 58 is wider (see Figs. 5 and 6) than the side 59 for a purpose to presently appear. The members 51 and 52 are dimensioned so that when they are telescoped together or are in a nested relation (see Fig. 2) they form a substantially 75

square shaped tube in which the side 58 of the member 52 is in side by side contiguous relation with one of the sides 56 of the member 51 and the side 59 is spaced inwardly from the other side 56 and the edge 62 of the side 58 engages the bridging portion 55 and the edge 63 of the side 59 is in spaced relation to the bridging portion 55.

To secure the members 51 and 52 in their nested relation one side 56 and the bridging portion 55 are depressed or crimped at spaced positions indicated by the numerals 66 and 67, respectively. The crimps 66 define projections on the inwardly facing surface of one of the sides 56 dimensioned so that when the members 51 and 52 are telescoped together the projections abut against the sides 59 of the member 52 and maintain the side members 56 and 59 in spaced relation. The crimps 67 define projections on the inner side of the bridging portion 55 that engage the edge 63 of the side 59 to space the latter away from the bridging portion 55. This construction in addition to spacing the members in a preselected manner to define the air inlet passageway 54 also provides a construction in which the sides 56 of the outer channel member 51 serve to grip the sides 58 and 59 of the inner channel member 52 when the members are in their assembled relation. The members are thus positively maintained in their nested relation. The projections formed by the crimps 66 and 67 are relatively narrow so that the air passageway 54 is in effect a continuous passageway extending lengthwise of the tubular section 43 in communication with the central passageway or gasway 53. With this construction the sidewalls defining the central passageway 54 are relatively smooth.

The particular dimensions of the air passageway 54 may vary. With one range construction I have found that with the construction shown in Figs. 2-5 wherein the inner passageway 53 is substantially square and is $\frac{3}{8}$ " along each side, that the side 59 should be spaced $\frac{1}{16}$ " from the side 56 and the outer edge 63 of the side 59 should be spaced $\frac{1}{16}$ " from the bridging portion 55.

As shown in Figure 1 only the vertical section of the flash means is constructed as described in the foregoing paragraphs. The horizontal tubular portion 41 in this instance is shown as an imperforate tube. Test experience shows that a flame may be propagated through the flash means with the tube 41 being imperforate. Where desired, however, the tube 41 may be of the same construction as the tubular section 43.

In Figs. 7, 8, 9 and 10 there is shown a modified form of the tubular section 43. In this instance it includes a central passageway 71 having two air entrance passageways 72 in communication with the central passageway 71. The section 43 is formed in this instance by channel members 73 and 74 telescoped together as described hereinbefore. The channel member 73 comprises a bridging portion 76 and spaced sides 77 and the channel member 74 comprises a bridging portion 78 and spaced sides 79. The sides 77 are of the same length and the sides 79 are of the same length. As described for the embodiment shown in Figs. 1-6 the members 73 and 74 are dimensioned so that when they are telescoped together in nested relation the sides 79 are spaced inwardly from the sides 77 and the edges 80 of the sides 79 are spaced from the bridging portion 76.

to define the air passageways 72 on opposite sides of the tubular section 43 to be in communication with the central passageway 71. The sides 77 and the bridging portion 76 are deformed to define crimps 81 and 82 at spaced positions therealong. The crimps 81 define projections on the inwardly facing surfaces of the sides 77 shaped so that when the members 73 and 74 are telescoped together the projections engage the sides 79 and maintain the sides 77 and 79 in spaced relation. The width of the bridging portion 78 is preferably slightly greater than the distance between projections 81 on the sides 77 so that the projections tend to maintain the members 73 and 74 in assembled relation. The crimps 82 formed on the inwardly facing portion of the bridging portion engage the extreme outer edges 80 of the sides 79 when the members 73 and 74 are telescoped together to space the edges 80 from the bridging portion 76 as best seen in Figs. 9 and 10.

This construction of a flash tube provides a very rugged construction and one that is not readily damaged during assembly or servicing thereof. Also with this construction the dimensions of the air passageway 54 (Figs. 1-6) and the air passageways 72 (Figs. 7 and 9) are accurately maintained. This construction is easy to manufacture and is also easy to assemble. Any desired length of flash tube constructed in accordance with the above may be utilized depending upon the distance that the flame is to be propagated. The channel members in this construction are in effect self-supporting in that they do not depend upon independent means such as a mounting at each end of the section for maintaining the channel members in spaced relation. As a result manufacturing costs of this tube are relatively low.

To better understand the function of the flash means and its operation, a description of the operation of the lighting system follows: The system as shown in Figure 1 is in its normal position with the oven cold and the constantly burning pilot burner 27 burning. When the operator of the range desires to use the range, he depresses the control knob 33 and rotates it. This opens the shut-off valve in the unit 18. Gas flows through the conduit 23, through the passageway 22 in the arm 21 to the pilot burner 19. Some of the gas flowing through the port defining the pilot burner 19 passes through the passageway 46 in the arm 21 between the oven pilot burner 19 and the sub-burner assembly 26. Simultaneously gas flows from the heat control unit 18, through the conduit 17 to the safety valve 16. The latter is in its closed position and prevents the flow of gas to the oven burner 11. The auxiliary valve 29 however is in its open position and gas flows through the conduit 28 to the sub-burner assembly 26. Gas issuing from the ports 50 in the sub-burner assembly 26 entrains a certain amount of air therein and this mixture passes upwardly through the vertical section 43 of the flash means. As the flow becomes established in the section 43 air is drawn into the central passageway 53 of the section 43 through the opening 54 along the entire length of the section 43. Flow velocity upward through the section 43 is maintained low enough to be non-turbulent. According to one theory which has been advanced to explain the successful operation of the present invention, throughout the entire length of the vertical section 43 there is thought to be gradation of air and gas across

the tube of increasing richness from the point adjacent the bridging portion 55, where the air passageway 54 effects communication with the central passageway 53 to the opposite wall of the passageway defined by the bridging portion 57. According to this theory, as the gas flows through the section 43 the flow characteristics are believed to comprise a series of co-existing columns of gas within the passageway 53 which increase in richness from a column A which is practically all air to the column G which is practically the same as the very rich mixture entering the bottom of the passageway 53. The smooth interior walls of the tubular section 43 assist in maintaining the flow of gas in the above described condition. Due to the flow characteristics of fluids, the laminar flow in the section 43 also is believed to be maintained for a considerable distance in the imperforate section 41 so that a number of horizontal layers which are extensions of the columns A through G of varying degrees of richness flow to the constantly burning pilot burner 27. One or several of these layers will be ignited by the constantly burning pilot burner 27 and the flame flashes through that layer and its corresponding column in the vertical portion down to the sub-burner assembly 26. According to this theory, the reason why this construction in practice has been found to provide a very dependable means of lighting the sub-burner 26 is because of the number of layers of air-gas mixtures flowing through the flash tubes 43 and 41, with at least one of the mixtures therein being of the right combustion characteristics to be ignited and flashed back to the sub-burner 26. While the foregoing theory may correctly point out why the present invention has proved successful for igniting the sub-burner from the top pilot burner, it is to be understood that the present invention is not restricted to this particular theory of operation concerning its successful flame propagating characteristics over a wide range of gases. Therefore, the theory outlined above is to be considered as only one possible explanation for the successful performance of the present invention.

Upon ignition of the sub-burner 26 a flame is flashed from the sub-burner 26 to the oven pilot burner 19 through the passageway 46. Upon ignition of the pilot burner 19 the flame 50 being directed against the thermocouple 37 heats up the latter.

When the knob 33 is depressed and rotated it also sets the timer mechanism 36 into operation and after a preselected time the safety valve 16 is opened. Gas then flows through the conduit 14, the mixing tube 13 to the oven burner 11. As soon as the gas issues from the ports of the oven burner 11 it is ignited by the pilot burner 19. The timing mechanism 36 operates to hold the safety valve in its open position until the thermocouple 37 has been heated to produce a current that energizes the electromagnet in the safety valve 16 and holds the latter in its open position.

When the safety valve 16 moves to its open position the auxiliary valve 29 is closed and the flow of gas to the sub-burner assembly 26 is stopped, thereby effecting an extinguishment of the flame in the sub-burner assembly.

To shut off the oven burner 11 the operator rotates the knob 33 to its initial position and the shut-off valve in the temperature control unit 18 is closed to prevent the flow of gas to the conduit 17, the safety valve 16 and the main burner 11 and also to the conduit 23 in communication

with the pilot burner 19. When the flow of gas to the oven burner 11 and the pilot burner 19 is stopped the burners are extinguished.

This application is a division of my co-pending application, Serial No. 642,941, filed January 23, 1946.

While I have shown several embodiments of my invention it will be understood that I do not wish to be limited thereto since many modifications may be made and I therefore contemplate by the claims to cover such modifications as fall within the true spirit and scope of my invention.

I claim:

1. A flash tube comprising a first U-shaped member formed by a bridging portion and spaced sides, a second U-shaped member in nested relation with the first member and formed by sides and a bridging portion in spaced relation to said bridging portion of the first member, one of said sides of said second member being wider than the other, said wide side being in side by side contiguous relation with one of the sides of the first member and abutting against the bridging portion of the first member, and the narrow side of said second member being in spaced side by side relation with the other side of the first member and being spaced from the bridging portion of the first member, spaced means formed on one of the members acting between said narrow side and said other side of the first member to maintain said sides in spaced relation and spaced means formed on one of the members acting between the narrow side and the bridging portion of the first member to maintain the edge of the narrow side in spaced relation to the bridging portion of the first member.

2. The combination recited in claim 1 in which the spaced means are defined by deforming one of the sides and the bridging portion of the first member at spaced positions therealong to define projections acting between the narrow side and one of the sides of the first member to maintain them in spaced relation and between the narrow side and the bridging portion of the first member to maintain the edge of the narrow side in spaced relation to the bridging portion of the first member.

3. A flash tube comprising a first U-shaped member formed by spaced sides and a bridging portion, one of said sides and said bridging portion having spaced crimped portions to define projections extending inwardly of the U-shaped member, a second U-shaped member formed by spaced sides and a bridging portion, one of said sides of the second member being wider than the other, said wide side being disposed in contiguous side by side relation with the other of the sides of the first member, the narrow side of the second member being in spaced side by side relation with said one side of the first member to be engaged by the projections thereon and the edges of the narrow side engaging the projections on the bridging portion of the first member to space the narrow side from the bridging portion of the first member.

4. A flash tube comprising a first U-shaped member formed by spaced sides and a bridging portion, said sides and bridging portion having spaced crimped portions to define projections extending inwardly of the U-shaped member, a second U-shaped member formed by spaced sides and a bridging portion, said sides of the second member disposed in spaced side by side relation with said sides of the first portion to be engaged by the projections on said first sides and the edges

of the sides of the second member engaging the projections on the bridging portion of the first member to space the edges of the sides of the second member from the bridging portion of the first member.

5. A flash tube comprising a pair of channel members each formed with spaced sides and a bridging portion, said channel members being telescoped together with the sides of the larger channel member overlapping the sides of the smaller channel member and the respective bridging portions in opposed spaced relation to define a central fuel passageway extending lengthwise of the channel members, one of said channel members being formed at one of its sides, at least, with spaced transverse protrusions abutting against the adjacent side of the other channel member to maintain said adjacent sides of the channel members in spaced relation between the transverse protrusions, whereby to define an air passageway between said channel sides leading outside the flash tube assembly, the larger channel member gripping the smaller channel member at the transverse protrusions to maintain the channel members in assembled telescoped relation, the edge of that side of the smaller channel member which is spaced from the adjacent side of the larger channel member being spaced from the bridging portion of the larger channel member when the channel members are in assembled telescoped relation, whereby to define an air passageway communicating between the central fuel passageway in the flash tube assembly and said air passageway between said adjacent spaced sides of the channel members.

6. A flash tube comprising a pair of channel members each formed with spaced sides and a bridging portion, said channel members being telescoped together with the sides of the larger channel member overlapping the sides of the smaller channel member and the respective bridging portions in opposed spaced relation to define a central fuel passageway extending lengthwise of the channel members, the larger of said channel members being formed with spaced inwardly-extending protrusions at its bridging portion and at least one side abutting against the adjacent side of the smaller channel member to maintain said adjacent side of the smaller channel member spaced from said side and bridging portions of the larger channel and defining an air passageway between the protrusions leading from outside the flash tube assembly into the central fuel passageway therein, said protrusions also gripping the adjacent side of the smaller channel member to maintain the channel members in assembled telescoped relation.

7. A flash tube comprising a pair of sheet metal channel members each formed with spaced sides and a bridging portion interconnecting the spaced sides, said channel members being telescoped together with the sides of the larger channel member overlapping the sides of the smaller channel member and the respective bridging portions in spaced opposed relation to one another to define a central fuel passageway extending lengthwise of the assembled channel members, the larger of said channel members at one side, at least, being formed with a plurality of inwardly-depressed portions spaced apart along its length abutting against the adjacent side of the smaller channel member to space apart said adjacent sides of the channel members

between the inwardly-depressed portions and to define air passageways between said channel member sides leading outside the flash tube assembly, said larger channel member at its bridging portion also being inwardly depressed at a plurality of portions spaced apart along its length abutting against the adjacent edge of the same side of the smaller channel member to space apart said edge of said smaller channel member side from the bridging portion of the larger channel member between the inwardly-depressed portions of the latter and to define air passageways between the bridging portion of the larger channel member and said side edge of the smaller channel member communicating between the central fuel passageway in the flash tube assembly and said passageways between the spaced sides of the channel members, said inwardly-depressed portions at the side of the larger channel member also gripping the adjacent side of the smaller channel member to maintain the channel members in assembled telescoped relation.

8. A flash tube comprising a pair of channel members each formed with spaced sides and a bridging portion, said channel members being telescoped together with the sides of the larger channel member overlapping the sides of the smaller channel member and the respective bridging portions in opposed spaced relation to define a central fuel passageway extending lengthwise of the channel members, one of said channel members being formed at both of its sides with spaced transverse protrusions abutting against the respective adjacent sides of the other channel member to maintain said adjacent sides of the channel members in spaced relation between the transverse protrusions, whereby to define air passageways between said channel sides leading outside the flash tube assembly, the larger channel member gripping the smaller channel member at the transverse protrusions to maintain the channel members in assembled telescoped relation, the edges of the sides of the smaller channel member being spaced from the bridging portion of the larger channel member when the channel members are in assembled telescoped relation, whereby to define air passageways communicating between the central fuel passageway in the flash tube assembly and said air passageways between said adjacent spaced sides of the channel members.

9. A flash tube comprising a pair of sheet metal channel members each formed with spaced sides and a bridging portion interconnecting the spaced sides, said channel members being telescoped together with the sides of the larger channel member overlapping the sides of the smaller channel member and the respective bridging portions in spaced opposed relation to one another to define a central fuel passageway extending lengthwise of the assembled channel members, the larger of said channel members at both of its sides being formed with a plurality of inwardly-depressed portions spaced apart along its length abutting against the respective adjacent sides of the smaller channel member to space apart said adjacent sides of the channel members between said inwardly-depressed portions and to define air passageways between said channel member sides leading outside the flash tube assembly, said larger channel member at its bridging portion also being inwardly depressed at a plurality of portions spaced apart along its length abutting against the adjacent edges of the sides of the smaller channel member to space apart said edges of said smaller channel member sides from the bridging portion of the larger channel member between the inwardly-depressed portions of the latter and to define air passageways between the bridging portion of the larger channel member and said side edges of the smaller channel member communicating between the central fuel passageway in the flash tube assembly and said passageways between the spaced sides of the channel members, said inwardly-depressed portions at the sides of the larger channel member also gripping the adjacent sides of the smaller channel member to maintain the channel members in assembled telescoped relation.
